UNITED STATES PATENT OFFICE.

WOLF STOLOFF, OF LONDON, ENGLAND.

EDUCATIONAL APPLIANCE.

Application filed October 22, 1923. Serial No. 670,085.

To all whom it may concern:

Be it known that I, WOLF STOLOFF, a subject of the King of Great Britain, residing at London, England, have invented a new and useful Improvement in Educational Appliances, of which the following is a specification.

This invention relates to educational appliances constructed as cabinets or frames with an opening provided with one or more shutters or blinds permitting different parts of a line of characters, or of a picture or the like to be exhibited or concealed, as desired.

In the improved educational appliance according to this invention, the shutters or blinds are made of an accordion pleated fabric arranged so that the pleats or folds of the fabric open out to allow the shutter or blind to be expanded or drawn over a part within the cabinet or frame which it is desired to conceal, or to fold closely together and thus entirely uncover the opening, permitting a character, inscription, picture or the like to be exhibited in its entirety within the opening or slot in the cabinet or frame.

In the accompanying drawing:

Figure 1 is a front view and

Figure 2 is a plan of a cabinet or frame having an opening in the front thereof, and provided with shutters or blinds, in accordance with this invention, arranged to cover or uncover the said opening.

Figure 3 shows a vertical section of the cabinet or frame on the line X—X, Figure 2.

As shown in the drawing, *a* is a cabinet or frame having rollers *b* mounted therein and rotatable by handles *c* so that a sheet *d* can be moved behind an opening *e* in the front wall of the cabinet or frame, in order to successively exhibit different parts of the sheet.

The opening *e* can be screened or covered wholly or in part by shutters or blinds made of pleated fabric *f*, such as canvas coated with a stiffening or other suitable material, or they may be made of slats or strips of relatively stiff material joined together by

strips of more flexible material, or of a relatively stiff material having its stiffness broken down along the lines of the folds.

One edge or end of each shutter or blind *f* is secured to the wall of the cabinet or frame by a batten *g* and the opposite edge or end *55* is secured to a stiffening bar or plate *h* provided with a handle *i*. The bars *h* are slidably mounted in guide grooves *j*, which also serve to guide the unattached edges of the shutters or blinds, and these bars are provided with springs *k* serving as brakes to hold each bar in any position to which it may be moved so that, for example, the blind is not drawn up or withdrawn from screening the opening *e* by the tendency of *60* the pleated material to assume its folded condition.

With this arrangement, the shutters or blinds can be extended to entirely cover or screen the opening *e* or they can be adjusted *70* to expose only a part of the sheet *d*.

What I claim is:

1. An educational appliance comprising a frame having guideways, a shutter made of pleated fabric coated with a stiffening material and having the stiffness broken down along the lines of the folds, said shutter having a pair of opposite edges movable in said guideways and having one of its other edges secured to said frame, and a bar to *75* which the edge of the shutter opposite to that secured to the frame is secured.

2. An educational appliance comprising a frame having guideways, a shutter made of strips of relatively stiff material joined together by strips of more flexible material, means for securing one edge of the shutter to the frame, a bar to which the opposite edge of the shutter is secured and movable in said guideways, and a spring brake associated with said bar and said frame to hold the bar in any position to which it may be moved in the said guideways.

W. STOLOFF.
